US0D1038362S

(12) **United States Design Patent** (10) Patent No.: **US D1,038,362 S**
(45) Date of Patent: ** Aug. 6, 2024

(54) **FAN**

(71) Applicant: **GD Midea Environment Appliances MFG. Co., Ltd.**, Guangdong (CN)

(72) Inventors: **Yufeng Ma**, Guangdong (CN);
Jianping Li, Guangdong (CN);
Chunyu Zhang, Guangdong (CN); **Zhi Li**, Guangdong (CN); **Zhifeng Liang**, Guangdong (CN); **Shubin Lin**, Guangdong (CN); **Qiangqiang Zhang**, Guangdong (CN); **Yingwen Huang**, Guangdong (CN)

(73) Assignee: **GD MIDEA ENVIRONMENT APPLIANCES MFG. CO., LTD.**, Guangdong (CN)

(**) Term: **15 Years**

(21) Appl. No.: **35/517,903**

(22) Filed: **Jun. 1, 2023**

(80) **Hague Agreement Data**

Int. Filing Date: **Jun. 1, 2023**

Int. Reg. No.: **DM/230342**

Int. Reg. Date: **Jun. 1, 2023**

Int. Reg. Pub. Date: **Jul. 28, 2023**

(30) **Foreign Application Priority Data**

Dec. 1, 2022 (CN) 202230804818.4

Dec. 6, 2022 (CN) 202230815725.1

Dec. 6, 2022 (CN) 202230815869.7

Dec. 22, 2022 (CN) 202230855198.7

(51) LOC (14) Cl. **23-04**

(52) U.S. Cl.

USPC **D23/378**

(58) **Field of Classification Search**

USPC D23/336, 364, 370, 378, 411

CPC F04D 25/00; F04D 25/08; F04D 25/088
